Inventor:
Raymond Duncan,

By A. Miers Attys.

UNITED STATES PATENT OFFICE.

RAYMOND DUNCAN, OF ELMIRA, NEW YORK.

MEANS FOR CONTROLLING THE OPERATION OF TALKING-MACHINES.

1,357,038.

Specification of Letters Patent. Patented Oct. 26, 1920.

Application filed December 3, 1919. Serial No. 342,106.

To all whom it may concern:

Be it known that I, RAYMOND DUNCAN, a citizen of the United States, residing at Elmira, in the county of Chemung and 5 State of New York, have invented a certain new and useful Improvement in Means for Controlling the Operation of Talking-Machines, of which the following is a full, clear, concise, and exact description, reference being had to the accompanying drawings, forming a part of this specification.

My invention relates to means for controlling the operation of talking machines, and particularly to means for automatically 15 controlling and especially automatically stopping the rotation of the record support.

One of the objects of the invention is to provide a simple, practical and effective mechanism of the class specified.

20 Another object of the invention is to obtain simplicity of construction and reliability and efficiency in operation.

Another object of the invention is to permit the use of the device with either hill 25 and dale or a laterally undulating zigzag record, and to make unnecessary any changes or adjustments, or vary any mountings or connections in the device in order to permit the use of the device with such 30 different records.

Another object of the invention is to secure the foregoing and other desirable results in a simple and expeditious manner.

In the accompanying drawings Figure 1 35 is an elevation of an end portion of a tone arm with a reproducer thereon and a device for automatically controlling the phonograph or talking machine operation embodying my present invention;

40 Fig. 2 is a cross section taken on line 2-2 in Fig. 1;

Figs. 3 and 4 are cross sections taken on lines 3-3 and 4-4, respectively, in Fig. 1.

In the drawings I show an end portion 45 of a tone arm 1 and a sound box or reproducer 2 mounted thereon. The connection between the tone arm 1 and sound box 2 involves a swivel connection formed by an elbow 3 in the tone arm and a tubular 50 projection or extension 4 on the sound box 2, said members 3 and 4 having a swivel connection with one another by means of a slot 5 and adjusting screw 6.

The sound box 2 is provided with a 55 holder 7 for a stylus 8, said holder 7 be-

ing connected with the sound box dia- phragm by a connection 9.

The stylus 8 is shown resting on a record 10 which is understood to be rotated by a suitable rotary support usually in the form 60 of a flat turntable 11.

I also show an arm or finger 11 carrying a pointed member 12 which like the stylus 8 is adapted to engage and travel in a groove on the record 10. The member 12 65 may be made of catgut or any suitable material adapted to rest upon and travel over the record 10 without injury to the same. Said member 11 is suspended at its upper end and arranged to depend or hang down- 70 wardly in a direction substantially parallel to the sound box 2. The lower end of the member 11 extends toward the stylus 8 so that the point 12 is not far removed from the stylus 8 on the record. Said member 75 11 is mounted at its upper end so as to permit a swinging motion relatively to the reproducer 2, a desirable arrangement being to mount said member 11 on a substan- 80 tially horizontal pivot 13. The pivot 13 is 85 preferably carried by a collar or attach- 90 ment 14 secured to the tone arm 1 as by screws 15.

As a preferred arrangement the attach- 35 ment 14 has a downwardly extending mem- 95 ber or flange 16 with a laterally projecting portion 17 at its lower end, said portion 17 being provided with a recess 18 in which the member 11 is confined. The member 11 is free to move in the recess 18 to a cer- 100 tain extent but is held against a wide move- 95 ment by the member 17. A contact mem- 105 ber 19 is carried by the stem or portion 16, the upper end of said contact 19 being held in position by a screw 20 and the lower end having a projecting end portion 21 adapted to make contact with the mem- 110 ber 11 when said member 11 is moved or 100 swung sufficiently toward the member 16. Adjustment of the position of the contact 110 19 is secured by an adjusting screw 22.

The upper end of the member 11 is in- 105 sulated from the attachment or support 14 by means of an insulating collar 24 and 110 electrical connection is made with said member 11 by means of a wire or conductor 25, screw 23 and block 23^a. Adjust- 115 ment of the member 11 in a longitudinal manner is permitted by an adjusting screw 26 forming part of a rod or bar 27 which 110

forms the upper end of the member 11, the lower end portion of the member 11 being formed by a separate member 28 having its upper end provided with a threaded 5 socket adapted to receive the threaded screw 26. An enlargement or nut portion 29 on the upper end of the member 28 permits said member 28 to be turned so as to secure the relative adjustment. Three of the sides 10 of the aperture 18—the three other than the one where the contact 19 is situated, are provided with insulating material 35—36 and 37, of shellac for instance for insulating the member 11 from the member 17. 15 The circuit terminating on the one hand at the contact 19 and on the other hand at the member 11 includes electro-magnetic mechanism for controlling a brake to stop the rotation of the rotary turntable 11. As 20 such braking mechanism is well known in the art it will not be described here.

In operation the stylus 8 and pointer 12 will travel in the record groove, the member 12 being somewhat in advance of the 25 stylus 8, considering the direction of said members 8 and 12. When said parts 8 and 12 approach the end of the record groove, the member 12 will arrive at the end first and upon reaching the end of the groove 30 will remain stationary, traveling in the circular groove with which the record is provided, while the stylus 8 continues to approach the end of the groove. In this way the member 11 will be moved toward the 35 contact 19 and will come in contact with the end 21 thereof and thus close the electrical circuit including the electro magnetic brake controlling mechanism, and will cause said brake to act upon the turntable 11 and automatically stop the operation of the machine. 40 When another record is played the members 8 and 12 will be again put in position, and will be separated from one another by the incline 34, and both will ride on the record 45 until nearly the end of the same when the companion member 12 will be stopped and the stylus 8 will catch up with it and thereby again close the circuit and set the brake.

It will be seen that the stylus companion 50 11 will maintain the proper position relative to the stylus 8 whether the sound box 2 be turned to play a hill and dale or a zigzag record, said member 11 being in proper position and not requiring any re- 55 mounting or rehanging or positioning or adjusting whether the reproducer 2 be turned into position crosswise of the tone arm 1 or lengthwise of the same.

It will be understood that changes and 60 modifications may be made without departing from the spirit of the invention.

What I claim is:

1. The combination of a talking machine tone arm, a reproducer carried thereby and 65 mounted for swivel adjustment and a com-

panion member coöperating with the sound box reproducer and mounted so as to assume a proper position relatively thereto when the tone arm is adjusted into either one of its positions. 70

2. The combination of a talking machine tone arm, a reproducer carried thereby and mounted for swivel adjustment, a companion member arranged to ride on the record and coöperating with the reproducer, 75 said companion member being provided with an elevated mounting permitting it to assume a proper relationship to the reproducer when the latter is adjusted to either one of its positions. 80

3. The combination of a talking machine tone arm, a reproducer carried thereby and mounted for swivel adjustment, a companion member arranged to ride on the record and coöperating with the reproducer, 85 said companion member being provided with an elevated mounting permitting it to assume a proper relationship to the reproducer when the latter is adjusted to either one of its positions; said elevated mounting 90 being on the tone arm in the rear of the pivotal connection thereof.

4. The combination of a talking machine tone arm, a reproducer carried thereby and mounted for swivel adjustment, a companion member arranged to ride on the record and coöperating with the reproducer, 95 said companion member being provided with an elevated mounting permitting it to assume a proper relationship to the reproducer when the latter is adjusted to either one of its positions; said elevated mounting comprising a bracket member attached to the tone arm in the rear of its swivel connection, said bracket member being provided with a contact with which said companion member is arranged to coöperate. 100

5. The combination of a talking machine tone arm, a reproducer carried thereby and mounted for swivel adjustment, a companion member arranged to ride on the record and coöperating with the reproducer, 110 said companion member being provided with an elevated mounting permitting it to assume a proper relationship to the reproducer when the latter is adjusted to either one of its positions, said elevated mounting comprising a bracket member attached to the tone arm in the rear of its swivel connection, 115 said bracket member being provided with a contact with which said companion member is arranged to coöperate, and means for adjusting said contact relatively to said bracket member. 120

6. The combination of a talking machine tone arm, a reproducer carried thereby and mounted for swivel adjustment, a companion member arranged to ride on the record and coöperating with the reproducer, said companion member being provided with an 125 130

elevated mounting permitting it to assume a proper relationship to the reproducer when the latter is adjusted to either one of its positions, said elevated mounting comprising a bracket member attached to the tone arm in the rear of its swivel connection, said bracket member being provided with a contact with which said companion member is arranged to coöperate, and the lower end of said bracket member being provided with a lateral projection having a recess in which said companion member is arranged to move and by which the movement of said member is limited.

15 7. The combination of a talking machine
tone arm, a reproducer carried thereby and
mounted for swivel adjustment, a companion
member arranged to ride on the record
and coöperating with the reproducer, said
20 companion member being provided with an
elevated mounting permitting it to assume a
proper relationship to the reproducer when
the latter is adjusted to either one of its po-
sitions, said elevated mounting comprising
25 a bracket member attached to the tone arm
in the rear of its swivel connection, said
bracket member being provided with a con-
tact with which said companion member is
arranged to coöperate, and means for adjust-
30 ing said contact relatively to said bracket
member, said companion member being piv-
oted to said bracket member.

8. The combination of a talking machine tone arm, a reproducer carried thereby and mounted for swivel adjustment, a companion member arranged to ride on the record and coöperating with the reproducer, said companion member being provided with an elevated mounting permitting it to assume a proper relationship to the reproducer when the latter is adjusted to either one of its positions, said elevated mounting comprising a bracket member attached to the tone arm in the rear of its swivel connection, said bracket member being provided with a contact with which said companion member is arranged to coöperate, and means for adjusting said contact relatively to said bracket member, said companion member being pivoted to said bracket member, and said companion member comprising two parts adjustable longitudinally with reference to one another.

9. The combination of a talking machine

tone arm, a reproducer carried thereby and 55
mounted for swivel adjustment, a companion
member arranged to ride on the record
and coöperating with the reproducer, said
companion member being provided with an 60
elevated mounting permitting it to assume
a proper relationship to the reproducer
when the latter is adjusted to either one of
its positions, said elevated mounting com- 65
prising a bracket member attached to the
tone arm in the rear of its swivel connection,
said bracket member being provided
with a contact with which said companion
member is arranged to coöperate, and means
for adjusting said contact relatively to said 70
bracket member, said companion member
being pivoted to said bracket member, and
said companion member comprising two
parts adjustable longitudinally with refer- 75
ence to one another, said two parts being a
threaded member and a socket member
adapted to receive the threaded portion of
said threaded member.

10. The combination of a tone arm 1 carrying a reproducer 2 having a stylus 8, a swivel connection consisting of members 3 and 4 between the tone arm 1 and reproducer 2, a bracket member 14 secured to the under side of the tone arm 1 in the rear of the swivel connection thereof, said bracket member 14 having a downwardly extending projection or portion 16, the lower end 17 of which consists of a recessed lateral extension, a spring contact 19 having its upper end secured to the portion 16 and its lower end provided with a lateral projection 21, an adjusting screw 22 carried by the member 16 and controlling the position of the contact 19, a companion member 11 having a point 12 adapted to travel in the record groove, said member 11 consisting of two parts 27 and 28, whereof the part 27 is pivoted to the bracket 14 and insulated therefrom, and whereof the part 28 is provided with a threaded socket adapted to receive the threaded end 26 of the member 27, said member 11 being arranged to work in the slot or recess formed in the transverse end portion 17 of the member 16. 80 85 90 95 100

In witness whereof I hereunto subscribe my name this 28th day of November, A. D. 1919. 105

RAYMOND DUNCAN.
